I claim the ornamental design for a combination sleeping bag, pillow and carrying bag, as shown and described.

DESCRIPTION

FIG. 1 is a perspective view of a combination sleeping bag, pillow and carrying bag showing my new design with the carrying bag shown inside-out at the rear of the article; FIG. 2 is a top plan view of FIG. 1;

FIG. 3 is a bottom plan view of FIG. 1;

FIG. 4 is a right-side elevational view of FIG. 1;

FIG. 5 is a left-side elevational view of FIG. 1;

FIG. 6 is a front elevational view of FIG. 1;

FIG. 7 is a rear elevational view of FIG. 1;

FIG. 8 is a perspective view thereof, illustrated in a collapsed configuration with the carrying bag shown right-side-in;

FIG. 9 is a front elevational view of FIG. 8, the rear elevational view being a mirror image thereof;

FIG. 10 is a left-side elevational view of FIG. 8, the right-side elevational view being a mirror image thereof;

FIG. 11 is a top plan view of FIG. 8; and,

FIG. 12 is a bottom plan view of FIG. 8.

The sinuous pattern shown throughout the interior of the carrying bag in FIGS. 8 and 11 is representative of the article bundled in the stored position.
